2,625,879

INKING MECHANISM FOR PRINTING MACHINES

Fred Spence, Sale, England, assignor to Linotype and Machinery Limited, London, England, a company of Great Britain

Application March 21, 1947, Serial No. 736,246
In Great Britain March 26, 1946

8 Claims. (Cl. 101—356)

1

This invention relates to inking mechanism for printing machines wherein a printing press bed carrying a printing surface or forme is reciprocated relatively to forme inking rollers and an impression cylinder.

In such machines the forme inking rollers, which receive ink from an ink supply source through a train of rollers, are adapted either to remain in position for contacting with the forme on the reciprocating bed during both strokes of the bed and so as to rotate in opposite directions in accordance with the direction of movement of the reciprocating bed, or are arranged to be lifted out of position for contacting with the forme during one stroke of the bed and to be rotated continuously in one direction.

It is the principal object of the present invention to provide an inking mechanism wherein an improved supply of ink is transmitted to the forme-inking rollers.

According to the invention, an inking mechanism for a printing machine having a reciprocating forme-carrying bed comprises an ink supply source, a plurality of forme inking rollers and independent trains of rollers for transmitting ink from the ink supply source to each forme-inking roller. Means may be provided for intermittently connecting each train of rollers to the ink supply source.

Preferably the ink supply source includes an ink drum rotating continuously in one direction and each train of rollers includes a transfer roller which makes controlled intermittent contact with the ink drum. Each train of rollers may also include a vibrator roller located between and in contact with a forme-inking roller on the one hand and the transfer roller on the other hand. The vibrator roller may be driven and during operation of the machine, may remain in contact with and driving connection with its associated forme-inking roller and transfer roller. The transfer roller may move into and out of contact with the ink drum while remaining in contact with the vibrator roller.

The movement of a transfer roller into and out of contact with the ink drum is preferably controlled so as to be in timed relation to the movement of the reciprocating bed and so as to limit the duration of contact between the ink drum and transfer roller to the time required to transfer sufficient ink for one inking of the forme. The transfer roller preferably contacts with the ink drum when the peripheral speeds of the ink drum and transfer roller are equal.

The ink supply source may also include an ink fountain roller, an ink drum rotating con-

2

tinuously in one direction, and a driven ductor roller which contacts alternately with the ink fountain roller and the ink drum. The ductor roller preferably contacts with a driven starter roller at an intermediate stage of its passage from the ink fountain roller to the ink drum.

Means may be provided for continuously rotating a forme-inking roller at uniform speed, and, during the printing stroke of the reciprocating bed, moving such roller into and out of position for contacting with the forme. The duration of contact of the movable forme-inking roller with the forme may be limited to the period when the bed is travelling at uniform speed.

15 The inking mechanism may be provided with means for moving the ink drum and a train of rollers to an inoperative position to enable the inking rollers to be removed or cleaned.

In order that the invention may be clearly understood and readily carried into effect, the same will now be described more fully with reference to the accompanying drawings in which:

Figure 1 is a side elevation of the general arrangement of an inking mechanism, certain details being omitted for clarity;

Figure 2 is an enlarged side elevation of part of the inking mechanism shown in Figure 1;

Figure 3 is a vertical sectional view of one side of the inking mechanism taken on the line III—III of Figure 2;

Figure 4 is a vertical sectional view of one side of the inking mechanism taken on the line IV—IV of Figure 2;

Figure 5 is a vertical sectional view taken on the line V—V of Figure 2;

Figure 6 is an enlarged side elevational view of the ink fountain;

Figure 7 is a plan view of the mechanism for operating the ink fountain roller;

Figure 8 is a vertical sectional view taken on the line VIII—VIII of Figure 7;

Figure 9 is a vertical sectional view of the main cam shaft;

Figure 10 is a side view of the ductor roller and associated mechanism;

Figure 11 is an enlarged side view, partly in section, of the mounting and associated mechanism for the inking rollers;

Figure 12 is a plan view of the forme roller frames and auxiliary forme roller frames in which certain of the inking rollers are mounted;

Figure 13 is a side view showing the auxiliary forme roller frames in raised position;

Figure 14 is a side view of the mounting and associated mechanism for the inking rollers;

Figure 15 is a side view of the driving mechanism for the inking rollers;

Figure 16 is a plan view of the mechanism shown in Figure 15; and

Figure 17 is an enlarged view of the gearing for driving the second vibrator roller.

Referring to Figures 1 and 2 of the drawings, the forme 1 on the reciprocating bed 2 is inked by two forme-inking rollers F¹, F², one of which (F¹) (hereinafter called the first forme roller) 10 remains in position for contacting with the forme 1 and so rotates in opposite directions in accordance with the direction of movement of the reciprocating bed 2, and the other of which (F²) (hereinafter called the second forme roller) is 15 lifted out of position for contacting with the forme 1 on the return stroke of the reciprocating bed 2 and is rotated continuously in one direction. Each forme roller F¹ or F² is supplied with ink through a separate train of rollers (a or b) 20 from an ink drum D rotating continuously in one direction. Each train of rollers a or b comprises a transfer roller T¹ or T² which makes intermittent contact with the ink drum D, and a vibrator roller V¹ or V² interposed between the 25 transfer roller T¹ or T² and the forme roller F¹ or F². Each vibrator roller V¹ or V² is in permanent contact with its associated transfer roller T¹ or T² on the one hand and the forme roller F¹ or F² on the other hand while the 30 inking mechanism is in normal running relation to the machine. The transfer and vibrator rollers associated with the first forme roller are hereinafter referred to as the first transfer roller and first vibrator roller, and the transfer and vibrator 35 rollers associated with the second forme roller are hereinafter referred to as the second transfer roller and second vibrator roller.

The ink drum D is intermittently supplied with ink by a doctor roller d which contacts alternately with the roller 3 of an ink fountain 4 and the ink drum D. The ink fountain 4 is carried by a fountain frame 5 adjustably clamped to forme roller frames 6 which, in a manner hereinafter more fully described, support certain of the inking rollers. A fine adjustment of the fountain frame 5 relatively to the forme roller frames 6 may be effected by the manipulation of bolts 7 (see Figures 6, 7 and 8) carried by plates 8 on the forme roller frames 6 and screwed into the fountain frame 5. A doctor blade 9 carried by a holder 10 co-operates with the fountain roller 3 and is provided with adjusting screws 11 for varying the gap between the fountain roller 3 and the blade 9.

The shaft 12 of the fountain roller 3 is carried by roller bearings in the fountain frame 5 and is intermittently rotated by the engagement of an oscillating pawl 13 with a ratchet wheel 14 keyed to the shaft 12. The pawl 13 is pivoted to one arm 15 of a bell-crank lever loosely mounted on the shaft 12, the other arm 16 of the bell-crank lever being connected by a link 17 to the stud 18 (see Figures 1 and 9) of a crank arm 19 on the main cam shaft 20 of the machine. The pawl 13 is normally held in engagement with the ratchet wheel 14 by means of a spring 21 which engages a pin 22 on the pawl 13. When it is desired to rotate the fountain roller 3 by hand, the pawl 13 may be held out of engagement with the ratchet wheel 14 by means of a hook 23 in the spring 21. For rotating the fountain roller 3 by hand, a detachable handle (not shown) is applied to the shaft 12 of the fountain roller 3.

The ink feed, that is the amount of rotation 75

imparted to the fountain roller 3, is adjusted by varying the number of teeth of the ratchet wheel 14 which are engaged by the pawl 13 at each working stroke thereof. For this purpose, an adjustable set wheel 24 is provided with a cam portion 25 which raises the pawl 13 out of engagement with the ratchet wheel 14 on the idle stroke of the arm 15 at a position determined by the angular position of the set wheel 24. The set wheel 24 is retained in position by a spring 26 engaging one or another of a number of notches 27 in the periphery of the set wheel.

The doctor roller d making alternate contact with the ink drum D and ink fountain roller 3 is mounted on a shaft 28 carried by bearings 29 (see Figure 10) adjustably clamped to levers 30 which are loosely mounted on a shaft 31 in the forme roller frames 6. The levers 30 are restrained from lateral movement by collars 32 on the shaft 31. The levers 30 are connected by links 33 to arms 34 (see Figures 1 and 9) secured to a shaft 35 which is rocked in its bearings in the machine frame by a lever 36 secured to the shaft 35 and having a roller 37 actuated by a cam 38 on the main cam shaft 20. The pressure of the doctor roller d against the ink drum D when it contacts therewith is limited by an adjustable spring connection 39, between the links 33 and arms 34.

The ink drum D is mounted on a shaft 40 carried in bearings 41 (see Figure 2) on arms 42 secured to a shaft 43 journalled in the forme roller frames 6. Sockets 44 adjustably carried in the arms 42 provide bearings for the shaft 45 of a rider roller 46 which makes contact with the upper surface of the ink drum D. One of the arms 42 is provided with a handle 47 by means of which the drum D can be moved from its operative position to an inoperative position (indicated by dot-and-dash lines in Figure 2) in which it may be retained by the engagement of a hook 48 with a stud 49 on one of the arms 42.

The shaft f¹ of the first forme roller F¹ (which, as mentioned above, remains in position for contacting with the forme 1) is carried at each side of the machine in a socket 50 (see Figure 11) adjustably mounted by means of a screw 51 and nut 52 in a block 53 secured to the forme roller frames 6.

The shaft v¹ of the first vibrator roller V¹ (see Figures 2, 11, 12 and 13) is supported at one end by a stud 54 on a bracket 55 secured to an auxiliary forme roller frame 56 mounted on a shaft 57 journalled in the forme roller frames 6. At its other end, the first vibrator roller V¹ is supported in a half bearing 58 formed in a forme roller frame 6, the half bearing 58 being capped by a similar half bearing 59 in another auxiliary forme roller frame 56 mounted on shaft 57.

The shaft t¹ of the first transfer roller T¹ (see Figure 11) is carried in sockets 60 (one at each side of the machine) which (as hereinafter more fully described) slide in blocks 61 clamped to the forme roller frames 6.

The shaft f² of the second forme roller F² (see Figures 11 and 14) is carried in sockets 62 which (as hereinafter more fully described) are slidably mounted in blocks 63 adjustably clamped to the forme roller frames 6. To facilitate manipulation of the second forme roller F², the shaft v² of the second vibrator roller V² is supported by half bearings 64 which are pivoted at 65 to the forme roller frames 6 (see Figure 13).

The shaft t² of the second transfer roller T² is supported by adjustable spring-controlled sockets 66 (see Figures 11 and 13) carried by

the auxiliary forme roller frames 56. Also carried by the auxiliary forme roller frames 56 are operating pins 67 and levers 68 for controlling the contact of the second transfer roller T² with the ink drum D and a spring stud 69 for breaking the contact of the first transfer roller T¹ with the ink drum D.

During normal operation of the inking mechanism, the auxiliary forme roller frames 56 are clamped to the forme roller frames 6 by hooks 70 (see Figures 11 and 13) on the auxiliary forme roller frames 56 engaging projections 71 on the forme roller frames 6. The hooks 70 are secured to a shaft 72 (see Figure 12) journalled in the auxiliary forme roller frames 56, and such shaft 72 is provided with a lever 73 by which it can be rotated, a spring plunger 74 being provided in the lever 73 to engage a recess in an auxiliary forme roller frame 56 and lock the lever 73 in position. To remove the inking rollers, the drum D is raised to the inoperative position indicated by dot-and-dash lines in Figure 2. The spring plunger 74 is then withdrawn and the lever 73 is raised to rotate the shaft 72 and release the hooks 70 from the projections 71 on the forme roller frames 56. A handle 75 on the lever 73 is then lifted to rotate the shaft 57 on which the auxiliary forme roller frames 56 are mounted and raise the auxiliary forme roller frames 56 until the spring plunger 74 engages a catch-plate 76 (as shown in Figure 13) and the lever 73 acts as a link to hold the auxiliary forme roller frames 56 in the raised position. During the raising of the auxiliary forme roller frames 56, the vibrator rollers V¹ and V² are lifted out of the bearings 58 and 64 in the forme roller frames 6 by means of hooks 77 and 78 carried by the auxiliary forme roller frames 56. The hooks 77 are carried by a plate 77a which is attached by screws 77b to the auxiliary forme roller frames 56. A screw 77b may be removed to allow a hook 77 to swing and free the shaft v¹ from the half bearing 59 when it is desired to remove the vibrator roller V¹ for cleaning purposes.

In normal running position, the transfer rollers T¹ and T² are respectively held out of contact with the ink drum D by spring studs 69 and springs 79 in the auxiliary forme roller frames 56 (see Figure 11) and are brought into contact with the ink drum D at an appropriate point in the cycle by means of operating arms 80 and 81 controlled by a cam 82 (see Figures 1 and 9) on the cam shaft 29 of the machine. Said cam 82 engages a roller 83 on a lever 84 secured to a shaft 85 journalled in the machine base, the roller 83 being held against cam 82 by a spring 86. Arms 87 secured to the shaft 85 are connected by links 88 to pivoted levers 89 carrying lifters 90 (see Figure 11) which contact with the operating arms 80 and 81 pivoted at 91 and 92 to the forme roller frames 6. The operating arms 80 and 81 are respectively furnished with adjusting screws 93 and 94 and lock nuts 95 and 96. In the case of the first transfer roller T¹, screws 93 contact with the lower ends of the slidable sockets 66 in which the first transfer roller T¹ is mounted. In the case of the second transfer roller T², screws 94 contact with push rods 97 which are slidably mounted in blocks 98 secured to the forme roller frames 6. The upper ends of push rods 97 engage the operating pins 67 bearing against levers 68 connected to the lower ends of the slidable sockets 66. As the cam roller 83 follows the

contour of the cam 82 the shaft 85 is turned and the transfer rollers T¹ and T² make and break contact with the ink drum D by the differential action of the spring 86 and the spring-pressed studs 69 and springs 79.

Plates (not shown) secured to the base of the forme roller frames 6 cover tommy holes 93a and 94a in the heads of the adjusting screws 93 and 94 to prevent any adjustment thereof except when the operating arms 80, 81, are in the raised position in which the transfer rollers T¹ and T² contact with the ink drum D.

To prevent an accumulation of ink on the forme rollers F¹ and F² when the machine is running with the impression cylinder I (see Figure 1) tripped out of printing position, a bar 99 on the shaft 85 is arranged to engage a cam 100 on the eccentric shaft 101 which, through rod 102, is connected to eccentric bearings 103 in which the shaft of impression cylinder I is mounted. When the cam 100 and bearings 103 are turned to trip the impression cylinder I, the cam 100 engages the bar 99 and prevents rotation of the shaft 85 and contact of the transfer rollers T¹ and T² with the ink drum D is prevented. The bar 99 can be flexed sideways to disengage the cam 100 when it is desired to run the inking mechanism with the impression cylinder I tripped.

Rotation of the ink drum D in one direction is effected by a gear wheel 104 (see Figure 2) keyed to the shaft which (through mechanism not herein described) effects reciprocation of the printing press bed 2, the gear wheel 104 driving the ink drum D through a gear train carried by the forme roller frames 6. Such gear train (see Figures 2, 5, 15 and 16) comprises gears 105, 106, 107, 108, which latter meshes with a gear 109 on shaft 40 of the ink drum D.

The second vibrator roller V² is also driven from gear 104 through the gears 105, 106, 107, the gear 107 meshing with a gear 109a (see Figure 3) which in meshes with a gear 110 on the shaft v² of the second vibrator roller V². The second vibrator roller V² frictionally drives the second transfer roller T² and second forme roller F² with which rollers it is in permanent contact.

The first vibrator roller V¹ derives its rotation from a toothed rack 111 (see Figures 2, 5, 15 and 16) attached to the printing press bed 2 and through gears 112, 113, 114, the gear 114 meshing with a gear 115 on the shaft v¹ of the first vibrator roller V¹. The first vibrator roller V¹ frictionally drives the first transfer roller T¹ and first forme roller F¹ with which rollers it is in permanent contact.

The gears 106 and 113 are co-axially but independently mounted on the stud 116, and the gears 107, 114, are co-axially but independently mounted on the stud 117. The gears 106 and 107 rotate uniformly, but the gears 113 and 114 reverse in direction of rotation at each stroke of the printing press bed 2. The gear 114 through an idler gear 118 mounted on a stud 119 drives the gear 120 which is loosely mounted on shaft 57 (see Figure 4). The gear 120 is integral with a gear 121 which latter meshes with a gear 122 on the shaft 123 of the starter roller 124. As indicated in Figures 2 and 10, the ductor roller d is adapted to come into contact with the starter roller 124. The function and method of operation of a starter roller for controlling and effecting the rotation of the ductor roller is fully described in the specification of Letters Patent No.

1,927,759. In the said specification, the ductor roller contacts alternately with an intermittently rotating ink fountain roller and the first distributor roller of a set of ink distributor rollers, and said ductor roller during its movement towards the said first distributor roller is caused by the driving or starter roller to rotate at a surface speed which corresponds to the surface speed of said first distributor roller. As hereinbefore described, according to the present invention, the ductor roller d is mounted for movement alternately into direct contact with the ink fountain roller 3 and into direct contact with the inking drum D, and moreover the starter roller 124, which is arranged for direct contact with the ductor roller during its passage from the ink fountain roller to the inking drum, is adapted by such contact to drive the ductor roller at the same surface speed as the inking drum at the time of contact therewith.

The vibrator rollers V¹ and V² and ink drum D are given a periodic axial reciprocation. The first vibrator roller V¹ is reciprocated by a cam-actuated lever 125 (see Figures 1, 5 and 9) which is pivoted on a stud 126 fixed in a bracket 127 secured to the machine base, the upper end of the lever 125 being provided with a roller 128 engaging a grooved collar 129 on the end of the shaft v¹, and the lower end of the lever 125 being provided with a roller 130 engaging a grooved cam 131 on the cam shaft 20. The lever 125 makes one complete movement backwards and forwards at each revolution of the cam shaft 20. The second vibrator roller V² is reciprocated by a lever 132 (see Figures 1, 2, 14 and 17) having a roller 133 engaging a grooved collar 134 on the end of the shaft v², the lever 132 being mounted on a vertical shaft 135 supported in bearings 136, 137, secured respectively to the machine base and a forme roller frame 6. An arm 138 secured to the lower end of the vertical shaft 135 is provided with a roller 139 engaging a grooved cam 140 carried on a stud 141 fixed to the machine base, the cam 140 being integral with a gear 142 which is driven by gears 143, 144, 145 (being integral with 144) and 146 from the cam shaft 20 at a speed of rotation which is two-fifths that of the cam shaft. The lever 132 is formed with an extension 147 provided with a roller 148 (see also Figure 5) which engages a grooved collar 149 on the shaft 49 of the ink drum D to impart a simultaneous reciprocation of greater amplitude and contrary sense to the ink drum D.

The second forme roller F² (which is lifted out of position for contacting with the forme 1 on the return stroke of the printing press bed 2) rotates with uniform angular velocity and for that reason it is allowed to contact with the forme 1 only when the printing press bed 2 is travelling at uniform speed during the printing stroke.

One of the blocks 63 (see Figures 1, 2, 11 and 14) in which the sockets 62 carrying the shaft f² of the second forme roller F² are slidably mounted has pivoted thereon an arm 150 furnished with an adjusting screw 151 and lock-nut 152. Such adjusting screw 151 is adapted to slide the forme roller socket 62 in the block 63 against the action of a spring 153 and by these means the contact between the forme roller F² and the forme 1 may be adjusted. On the underside of the pivoted arm 150 is a projecting lug 154 resting on the base of the forme roller frame 6 and on the underside of the arm 150 is a facing 75 of the ductor roller d. The diameter of the ink

155 with which a lifter 156 contacts. The lifter 156 is pivotally connected to a lever 157 which is pivoted on a stud 158 secured in the machine base. The lever 157 is connected by a link 159 to an arm 160 secured to the rocking shaft 35 by which the ductor roller d is oscillated in the manner already described. Thus, when the ductor roller d is in contact with the ink fountain roller 3, the second forme roller F² is lifted out of position for contacting with the forme 1 and the printing press bed 2 is on the return stroke. The above mechanism is duplicated on the other side of the machine and both ends of the forme roller F² are lifted simultaneously.

When the second forme roller F² is lifted out of position for contacting with the forme 1, the second vibrator roller V², being carried in fixed bearings 64, does not move. At this stage, the second transfer roller T² is out of contact with the ink drum D but still in contact with the second vibrator roller V². The movement of the second forme roller F² and the second transfer roller T² is comparatively small and takes place along a line at right angles to a line joining the centre of the respective roller to the centre of the second vibrator roller V². Thus, the effect of such movement is virtually the same as though the second forme roller F² and second transfer roller T² rolled around the circumference of the second vibrator roller V² and driving contact between the rollers is unaffected.

The quantity of ink supplied to the forme rollers F¹ and F² at each printing operation is dependent partly upon the thickness of the film of ink on the ink fountain roller 3 (determined by the setting of the ink fountain blade 9) and partly upon the angular advance of the ink fountain roller 3 (determined by the position of the set wheel 24).

The supply of ink is automatically interrupted when the impression cylinder I is tripped in order to avoid congestion of ink on the rollers of the inking mechanism. For this purpose a rod 161 (see Figures 1, 2 and 8) is connected at its upper end to the eccentric bearing 163 and at its lower end to a bell-crank lever 162 adjustably connected to the horizontal link 163. The link 163 is adjustably connected to the bell-crank lever 164 which is connected to the downwardly extending part 165 of a hook-shaped cam 166. Rotation of the eccentric bearing 163 brings the cam 166 into engagement with a pin 167 on the pawl 13 which is thus raised out of engagement with the ratchet-wheel 14.

New ink from the ink fountain roller 3 undergoes preliminary distribution between the starter roller 124 and the ductor roller d before being applied to the ink drum D.

With the maximum amount of ink feed about one quarter of the surface of the ductor roller d receives ink from the ink fountain roller 3, actuating cam 38 of the ductor roll moving means being so shaped that such roll makes only one quarter of a revolution in contact with the fountain roller 3. By preliminary distribution with the starter roller 124 (which roller has a diameter half that of the ductor roller d) approximately half of this ink is transferred to the opposite surface of the ductor roller d before the ductor roller d contacts with the ink drum D. The ink is then applied to the surface of the ink drum D in areas of colour alternating with blank spaces of the same width, i. e. one quarter of the circumference of the ductor roller d. The diameter of the ink

drum D is not an exact multiple of the diameter of the ductor roller d so that after one complete revolution of the ink drum D the areas of colour commence to overlap the blank spaces and the point of application of the ink travels progressively around the ink drum D in subsequent cycles of operation. The ductor roller d remains in contact with the ink drum D for approximately one and one-third revolutions of the drum D. The circumference of the ink drum D may be greater than the length of the forme 1 on the printing press bed 2 and the amount of ink carried on the ink drum D is sufficient for several inkings of the forme 1.

The movement of the transfer rollers T¹ and T² is arranged so as to be in timed relationship with the movement of the printing press bed 2 and so as to cause the transfer rollers T¹ and T² to contact at the appropriate time with the continuously rotating ink drum D. Thus, the movement of the reversible first transfer roller T¹ is controlled so that the transfer roller T¹ contacts with the ink drum D when the peripheral speeds of the ink drum D and transfer roller T¹ are equal.

The duration of the contact between the transfer rollers T¹ and T² and the ink drum D is limited to the time required to pick up enough ink for one printing operation, and this contact is timed and arranged so that new ink does not arrive at the bottom (or forme contacting position) of the forme rollers F¹ and F² until the forme 1 has passed that position. This allows the maximum possible time for the complete milling of the ink before its application to the forme 1.

Having described my invention, I declare that what I claim and desire to secure by Letters Patent is:

1. In inking mechanism for printing machines, the combination with a forme-carrying bed, forme-inking rollers relatively to which the forme-carrying bed is reciprocated, and an ink fountain roller from which ink is transferred to the forme-inking rollers, of an ink drum continuously rotating in one direction, means for transferring ink from the fountain roller to the ink drum, transfer rollers for transferring ink from the ink drum to the forme-inking rollers, means for rotating the transfer rollers, slideable sockets in which the transfer rollers are mounted, mechanism for moving the sockets to bring the transfer rollers into and out of contact with the ink drum and a cam controlling said mechanism so that the transfer rollers contact with the ink drum when the peripheral speeds are equal and the movement of the transfer rollers is timed and arranged so that new ink does not arrive at the forme-contacting part of the forme-inking rollers until the forme carried by the bed has passed the ink receiving position and further time is allowed for milling of the ink before its application to the forme.

2. A combination according to claim 1 in which each transfer roller is located in a separate train of rollers comprising a driven vibrator roller and a forme-inking roller, each vibrator roller being in permanent contact with its associated transfer roller on the one hand and the forme roller on the other hand.

3. A combination according to claim 1 including a ductor roller, mechanism for moving the ductor roller alternately into contact with the ink fountain roller and the ink drum and a driven starter roller with which the ductor roller contacts during its passage from the ink fountain roller to the ink drum and by which the ductor

roller is driven at the same surface speed as the ink drum.

4. In inking mechanism for printing machines, the combination with a forme-carrying bed, forme-inking rollers relatively to which the forme-carrying bed is reciprocated, and an ink fountain roller from which ink is transferred to the forme-inking rollers, of an ink drum continuously rotating in one direction, means for transferring ink from the fountain roller to the ink drum, transfer rollers, means for moving the transfer rollers into and out of contact with the ink drum, driven vibrator rollers with which the transfer rollers and forme-inking rollers contact, a pivoted auxiliary frame in which one transfer roller is mounted, half bearings in which the vibrator rollers are mounted and hooks carried by the auxiliary frame which on a pivotal movement of said frame withdraw the vibrator rollers from the half bearings to allow access to the inking rollers for cleaning and adjustment.

5. In inking mechanism for printing machines, the combination with a forme-carrying bed, forme-inking rollers relatively to which the forme-carrying bed is reciprocated and an ink fountain roller, of an inking drum continuously rotating in one direction from which ink from the fountain roller is transferred to the forme-inking rollers, a ductor roller mounted for movement alternately into direct contact with the ink fountain roller and into direct contact with the inking drum for transferring ink from the fountain roller to the inking drum, mechanism for effecting such movement of the ductor roller, and a driven starter roller arranged for direct contact with the ductor roller during its passage from the ink fountain roller to the inking drum and adapted by such contact to effect preliminary distribution of ink on the ductor roller during its passage from the fountain roller to the inking drum and to drive the ductor roller at the same surface speed as the inking drum at the time of contact therewith.

6. The combination according to claim 5, wherein the ductor roller moving mechanism includes means for causing said mechanism to maintain the ductor roller for only part of one revolution in contact with the fountain roller so as to receive ink on only a portion of its surface circumferentially and wherein the diameter of the inking drum, while much greater than that of the ductor roller, is not an exact multiple of the diameter of the ductor roller, whereby the ink is applied to the inking drum during one revolution thereof in areas of colour alternating with blank spaces and after one revolution thereof in areas of colour which commence to overlap the blank spaces, the point of application of the ink traveling progressively around the inking drum during subsequent cycles of operation.

7. The combination according to claim 6, in which the control mechanism controls the ductor roller moving mechanism so that during contact of the ductor roller with the fountain roller ink from the fountain roller is received on about one quarter of the surface circumferentially of the ductor roller and in which the starter roller has a diameter which is half that of the ductor roller, whereby due to the contact of the starter roller with the ductor roller during the passage of the latter from the ink fountain roller to the inking drum ink is transferred by preliminary distribution to the circumferentially opposite quarter surface of the ductor roller and thus applied to

the inking drum in areas of colour alternating with blank spaces of the same width.

8. The combination according to claim 7, wherein the surface of the inking drum is of a size to carry sufficient ink for several printing operations and including, as additional elements, transfer rollers for transferring ink from the inking drum to the forme-inking rollers, and mechanism for moving the transfer rollers into and out of contact with the inking drum, said mechanism being timed to maintain the transfer rollers in contact with the inking drum for a period sufficient only to enable the transfer rollers to pick up enough ink for one printing operation.
